UNITED STATES PATENT OFFICE.

GEORGE M. ERVIN, OF JOHNSTOWN, PENNSYLVANIA, ASSIGNOR TO THE LORAIN STEEL COMPANY, A CORPORATION OF PENNSYLVANIA.

RAILWAY-TRACK STRUCTURE.

SPECIFICATION forming part of Letters Patent No. 784,735, dated March 14, 1905.

Application filed August 1, 1904. Serial No. 219,020.

To all whom it may concern:

Be it known that I, GEORGE M. ERVIN, of Johnstown, in the county of Cambria and State of Pennsylvania, have invented a new and useful Improvement in Railway-Track Structures, of which the following is a full, clear, and exact description, reference being had to the accompanying drawings, which form a part of this specification.

10 My invention relates to railway-track structures—such as frogs, crossings, mates, and switches—and is designed to provide a novel form of structure having those parts which are subject to the greatest wear formed by a harder and more durable material and in which the parts are secured together in a manner to withstand the severe service which they receive in use and also in a manner to reduce the shop-work necessary to their proper fitting and assembly.

15 With these objects in view my invention consists in the novel construction and combination of parts, all substantially as hereinafter described, and pointed out in the appended claims, reference being had to the accompanying drawings, in which—

20 Figure 1 is a plan view of a frog embodying my invention; Figs. 2 and 3, sections taken on the lines 2 2 and 3 3, respectively, of Fig. 1; Fig. 4, a plan view of a frog of modified construction; Figs. 5 and 6, sections taken on the lines 5 5 and 6 6, respectively, of Fig. 4; Fig. 7, a plan view of a frog embodying a second modification; Fig. 8, a section on the line 8 8 of Fig. 7; Fig. 9, a plan view showing the invention applied to a right-angled crossing of the three-rail type; Fig. 10, a plan view of a switch-mate embodying the invention; Figs. 11, 12, and 13, sections taken on the lines 11 11, 12 12, and 13 13, respectively, of Fig. 10; and Fig. 14, a plan view of a tongue-switch embodying the invention.

25 Referring first to the construction shown in Figs. 1, 2, and 3, the letter A designates a central body of cast metal, preferably steel, in which is cored a pocket for a removable wear plate or center B, which may be of manganese steel, chrome steel, or other specially hard steel, such as is now generally used in the

manufacture of these wear plates or centers. Said piece A is also cast with the arms or extensions a and a' , in which are cored seats for the end portions of the connecting-rail members A'. These pockets correspond generally in section to the section of the lower portions of the rail members, but are made of sufficient size so that after the rail has been placed therein there will be left a surrounding space to receive a filling b of spelter, Babbitt, or other like material which can be poured therein while in a fluid state. The arms a also form the bearing or easing rail members a^2 , and the arms a' in a similar manner form the guard-rail members a^3 . A² designates anchor-bolts to prevent creeping of the rail members A'; but these may be omitted and the said members be provided with anchor projections of any suitable character, which will be embedded in the filling b, or they may be provided with openings through which said material can flow to form anchors.

30 The construction shown in Figs. 4, 5, and 6 is the same as that just described, except that the separate plate or center B is omitted and the central body A is itself directly provided with the intersecting track-surfaces a^4 . In this construction the said body is preferably cast entirely of a specially hard steel.

35 In the construction shown in Figs. 7 and 8, instead of forming the bearing and guard rail members a^2 and a^3 integrally with the central body, separate rolled or cast rail-sections C C' are employed, these being seated in pockets in the arms of said body by the side of and in the same manner as the running-rails A' and provided with a similar surrounding filling, as clearly shown in Fig. 1. Separate chocks a^5 are in this modified type preferably employed between the rails A' and the bearing-rails C. In this type of construction I have shown a solid center; but it is obvious that, if desired, a removable plate may be employed, as in Fig. 1.

40 Fig. 9 shows the invention applied to a right-angled crossing of the three-rail type, the method of construction being the same as that shown in Figs. 7 and 8, except that a removable center plate is shown. The center may,

however, be formed integrally. In this figure D designates the main running-rails, D' the bearing-rails, and D² the guard-rails. Figs. 10, 11, 12, and 13 show the invention applied to a switch-mate. The central cast body E is provided with a seat for a renewable plate F and with arms or extensions G, in which are formed the seats or pockets for the connecting rail members H.

10. Fig. 14 shows a tongue-switch of similar type of construction, corresponding parts being lettered the same as in Figs. 10, 11, and 12.

If desired, the cast-metal central body can be made to form a direct support for the heads 15 of the rails. This is shown at h in Figs. 2, 8, 11, and 13. If desired, however, the heads may be carried on the filling b, as shown in Fig. 5.

It will be noted that in each of the several 20 modifications shown there is employed the feature of a central body provided with pockets to seat the connecting rail members, said pockets being made sufficiently large to receive around the rail members a body of filling material introduced in a fluid state. In the manufacture of this structure the body portion is first cast from patterns. The rail members are then cut to the desired length and of the proper shape at their inner ends to fit the center piece or plate. They are then placed in 25 the pockets and properly alined and positioned. The molten spelter or other like material is then poured to fill the pockets. This method of construction reduces very largely the amount of shopwork, since the filling will 30 take care of variations in the sections of the rail members and also within certain limits deficiencies in the angle of the intersecting tracks. The amount of fitting required is 35 therefore reduced to a minimum. It is also possible to reduce the number of patterns required, since, as above noted, by means of the filling standard patterns will take care of variations in the rail-sections and in the angle. 40

45. A further advantage of the construction is that the parts may be securely held together without depending upon bolts, which, as is well known, constantly tend to work loose.

My invention, as shown, is applicable to 50 both T and girder rail construction and to both steam and street track use and is capable of various embodiments besides the particular ones which I have shown and described and to which I do not limit myself.

55. Having thus described my invention, what I claim as new, and desire to secure by Letters Patent, is—

1. In a railway-track structure, the combination with a body portion formed with rail-seating pockets, of rail members seated in said pockets, and a filling in said pockets around the rail members.

2. In a railway-track structure, the combination with a body portion formed with arms, 60 rail-seating pockets formed in said arms and

larger than the rails which they are to seat, rail members seated in said pockets, and a filling material about the pocketed end portions of said rails.

3. In a railway-track structure, the combination with a body portion formed with rail-seating pockets which are of greater area than the portions of the rails which they are to seat, of rail members seated in said pockets, and a filling surrounding the pocket portions of said rails, said filling being introduced in a fluid or molten state. 75

4. In a railway-track structure, a body portion formed with seating-pockets for the connecting-rails of the structure, said pockets being of sufficiently larger area than the portions of the rails which they are to seat to leave space for a filling material. 80

5. In a railway-track structure, a body portion formed with seating-pockets for the connecting-rails of the structure, said pockets corresponding generally in shape to the portions of the rails which they are to seat, but materially larger. 85

6. In a railway-track-crossing structure, a body portion carrying the intersecting track-surfaces, and formed with extensions provided with pockets for receiving the running-rails, said extensions also forming the guard-rail members of the structure. 90

7. In a railway-track-crossing structure, a body portion carrying the intersecting track-surfaces, and formed with extensions provided with pockets to receive the running-rails, said extensions also forming the bearing or easing 100 rail member of the structure.

8. In a railway-track-crossing structure, a body portion carrying the intersecting track-surfaces, and formed with extensions provided with pockets to receive the running-rails, said 105 extensions also forming the bearing and the guard-rail members of the structure.

9. In a railway-track structure, a body portion formed of cast-steel, and provided with pockets to seat connecting-rail members, and also with a pocket to seat a removable wear member. 110

10. In a railway-track structure, a cast body portion having one or more bearing or guard rail members formed integrally therewith, and 115 provided with a pocket to receive a removable intersection piece or plate.

11. In a railway-track structure, a body portion formed with a pocket to seat a removable intersection or wear member, and with extensions formed with pockets for receiving connecting-rails, said extensions also forming rail members. 120

12. In a railway-track structure, the combination with a body portion carrying the intersecting track-surfaces, and formed with pocketed arms or extensions of rail members seated in the pockets of said arms or extensions with their inner ends abutting the track-surfaced portion of said body. 125 130

13. In a railway-track structure, the combination with a body portion carrying track-surfaces, and formed with arms or extensions provided with rail-seats, of rail members in said seats, a filling material surrounding the seated portions of the rail members, and means for anchoring said members.

14. In a railway-track structure, the combination with a cast-metal body portion formed 10 with a plurality of rail-seating pockets, of rail members seated in said pockets in a filling of softer metal.

15. A body portion for use in the manufacture of railway-track structures, comprising a casting formed with a plurality of arms or extensions, each of which is recessed to seat the end portions of one or more rail members, the rail-seating recesses being of considerably larger area than the rail members 15 to be seated therein.

16. A body portion for use in the manu-

facture of railway-track structures, comprising a casting formed with a plurality of arms or extensions, each of which is recessed to seat the end portion of one or more rail members, 25 the rail-seating recesses being of considerably larger area than the rail members to be seated therein, and said arms or extensions themselves forming rail members.

17. In a railway-track structure, a body portion formed with a rail-seating recess of larger area than the rail, a rail seated in said recess, and a filling in said recess about the seated portion of the rail and applied thereto in a fluid state after the rail is seated. 30

In testimony whereof I have affixed my signature in presence of two witnesses.
